CONTROL MECHANISM

James Amedeo Conterio, Chicago, Ill.

Application May 21, 1937, Serial No. 144,028
In Italy May 23, 1936

1 Claim. (Cl. 244—83)

This invention relates to improvements in propelling mechanisms and more particularly to propelling mechanism for air craft, water craft and the like. One object is to provide means adapted to be built into air gliders whereby this type of transportation may be adapted to travel with, or against, air currents; to rise and dip as may be desired and to steer readily.

A further object is to provide foot-operated power means for small water craft whereby great speed may be attained with little effort, and instantly responsive steering means provided.

A further object is to provide propelling mechanism together with steering means and altitude control for air craft that is positive and efficient in operation, simple in construction and dependable in use.

With the foregoing and other objects in view the invention consists in the combination and arrangement of parts to be hereinafter fully described, pointed out in the claim and illustrated in the accompanying drawings which form a part of this application for patent and in which—

Fig. 1 is a view of the mechanism in side elevation.

Fig. 2 is a fragmentary plan view, enlarged, of Fig. 1.

Fig. 3 is an enlarged cross sectional view through Fig. 2 on the line 3—3 thereof.

Fig. 4 is a similar view on the line 4—4 of Fig. 2, but looking in the opposite direction.

Fig. 5 is an enlarged view, in elevation, of a locking pin employed.

Fig. 6 is a plan view of the gearing employed and the supporting framework therefor.

Fig. 7 is an enlarged vertical transverse sectional view through Fig. 6 on the line 7—7 thereof.

Fig. 8 is a similar view on the line 8—8 of Fig. 6, looking in the opposite direction.

Fig. 9 is a top plan view of Fig. 10.

Fig. 10 is a view of Fig. 9 in elevation.

Fig. 11 is an enlarged fragmentary view, in plan, of the double-toothed driving gear and meshing pinions, with supporting frame.

Like reference characters denote corresponding parts throughout the several views.

The present invention includes a frame having a steering post jacket 1 connected by the top bar 2 to the seat post 3 provided with the seat 4. Journaled in a bearing at the lower end of the seat post is the pedal shaft 5 provided with the pedals 6 and fast to said pedal shaft is the double-toothed drive gear 7 which, in tandem

machines, etc. is in mesh with the pinion 8 of shaft 9 that runs to the next seat post of the tandem. Also in mesh with the drive gear is the pinion 10 of the stub shaft 11, journaled in the framework 12 secured by brace 13 to the seat post and by brace 14 to the pedal-shaft bearing. The frame piece or block 12 is connected by brace rods 15 to a block 16 secured by braces 17 to the steering post jacket 1.

Fast to the stub shaft 11 is the large gear 18 in mesh with pinions 20, 21 fast, respectively, upon transmission shafts 22, 23 also journaled in the blocks 12, 16, said shafts 22, 23 having fast upon their forward ends the large gears 24, 25 both in mesh with the pinion 26 of the propeller shaft 27 journaled in a bearing in the block 16, said propeller shaft having fast thereupon the propeller 28. Rotation of the drive gear 7 will cause relatively fast rotation of the pinion 10, shaft 11 and gear 18 in mesh with the pinions 20, 21 thus causing fast rotation of the large gears 24, 25 in mesh with the propeller shaft 27 driven thereby at high speed. To facilitate assembly of the handle bar 1a it is made in two sections, the meeting ends being threaded and screwed together as shown at 1b in Fig. 2. The handle bar is secured to the steering post by the head 29 having threaded therein the vertical rack 31 for engagement by the pin 32 that extends through the casing 33 secured by the clamp 34 to the handle bar, a spring 35 within said casing serving yieldingly to retain the pin in locking engagement with the rack teeth.

The pin 32 is slotted to receive a screw 36 to prevent the pin from turning in its bearings. A cord 36 secured to the pin passes through the guide collar 37 clamped to the handle bar and through a like collar 38 and is secured to one end of the hand lever 39 fulcrumed to a strap 40 made fast to the hand grip 41 of the handle bar. The spring 42 of lever 39 yieldingly retains the same in off position so that the handle bar is releasably locked to the rack 31. When the lever 39 is manually pressed toward the hand grip the cord 36 withdraws the pin 32 from the rack thus permitting the handle bar to be raised or lowered and when adjusted as desired the lever is released and the pin and rack again locked in engagement with each other. A cord 43 running from the handle bar to the aileron, not shown, serves to transmit movement of the former to the aileron to cause an altitude adjustment of the air craft. The cord 43 is fast to the pin 43a that extends through the slot 43b in 55

the head 28 and into the handle bar and prevents longitudinal movement of the same in the head.

Fast to the steering post jacket 1 is the horizontal rack 44 over which the angular pin 45 works, said pin being carried by the casing 46 and yieldingly pressed by the casing spring 47 into locking engagement with said rack, said casing being secured by the clamp 48 to the handle bar. The head end of the pin 45 is connected by the cord 49 to the handle bar hand grip 41a provided with a lever and lever spring identical with that shown for the cord 38. A collar clamp 50 secured to the steering post 40a carries the screw eyes 51, 52 to which the cords 53, 54 are secured that run to the rudder for control of the same. When the pin 45 is disengaged from the rack 44 the handle bar may be manually moved, together with the steering post, to turn the rudder but when not changing the course of the vehicle the pin is permitted to hold its normal engagement with the rack. I have illustrated what I believe to be the simplest

and best embodiment of my invention, describing the same in terms of description only and not as terms of limitation, as modifications in details of construction may be made without departing from the spirit of my invention.

What is claimed is:

In an aircraft having a control surface, a control mechanism therefor comprising a sectional handle bar, a steering post, a head in said steering post receiving said handle bar sections, an annular rack upon one end of said head, a clamp carried by one handle bar section and spaced from said rack, a pin carried by said clamp in yielding engagement with said rack, manually actuated control means for said pin connecting the same and the other end of one handle bar section, said means including a cord, guides for said cord carried by said handle bar section, a second pin carried by said head, and a cord connecting said second pin and said control surface.

JASMIN ANTONIO CONTRERIO.
